UNITED STATES PATENT OFFICE.

JOHN M. WILLIAMS, JR., OF GREENWICH, CONNECTICUT.

ILLUMINATED SIGN.

1,054,954.

Specification of Letters Patent.

Patented Mar. 4, 1913.

Application filed March 20, 1912. Serial No. 685,059.

To all whom it may concern:

Be it known that I, JOHN M. WILLIAMS, Jr., a citizen of the United States, and resident of the town of Greenwich, in the county 5 of Fairfield and State of Connecticut, have invented certain new and useful Improvements in Illuminated Signs, of which the following is a specification.

My invention relates to illuminated signs, 10 more particularly to signs employing reflected light.

It has for its object to provide a sign having a casing provided with openings representing letters, figures, designs or other devices, reflectors within said casing extending over said openings and adapted to reflect light through the same and illuminating means also within said casing adapted to project light upon the reflectors.

20 It has for a further object to provide reflectors, each having a forwardly, laterally and downwardly facing concave surface adapted to reflect light through the openings in the casing and adapted to produce the 25 maximum amount of reflected light from the minimum amount of illuminating means.

It has for a still further object to produce the appearance of a number of individual lights, by placing a number of reflectors 30 across the openings, in the casing, forming the letters, figures, designs or other devices and directing light on said reflectors.

In the drawings: Figure 1 is a fragmentary front view, partly broken away, of my 35 invention. Fig. 2 a transverse vertical sectional view, taken on the line 2—2 of Fig. 1. Fig. 3 a horizontal sectional view, taken on line 3—3 of Fig. 1. Fig. 4 a fragmentary top plan view, showing one of the reflectors. 40 Fig. 5 a fragmentary front view, showing one of the reflectors. Fig. 6 a fragmentary horizontal sectional view, showing one of the reflectors. Fig. 7 a fragmentary horizontal sectional view of a modified form of 45 my invention. Fig. 8 a fragmentary front view of another modified form of my invention. Fig. 9 a fragmentary front view of another modified form of my invention. Fig. 10 a fragmentary sectional view, taken 50 on the line 10—10 of Fig. 9. Fig. 11 is a detail sectional view of one of the reflectors shown in Figs. 9 and 10.

Referring to the drawings, in which like reference characters designate corresponding parts, 55 1 designates the casing the inner faces of the walls of which are adapted to

reflect light. The front and rear walls 2 and 3 respectively, of the casing, may be either opaque or translucent and are provided with openings 4 in the form of the 60 letter T. A number of concave reflectors 5 are secured across the openings 4 to the inner faces of the walls 2 and 3 along the peripheries of the openings, in spaced relation to each other, and extend diagonally inwardly and laterally from said walls and each reflector is provided with a surface 6 adapted to reflect light forwardly, downwardly and laterally through said openings.

Within the casing, at the side thereof to 70 which the reflecting surfaces 6 of the reflectors 5 face, is provided illuminating means, shown in the drawings as an incandescent electric lamp 7. Lenses 8 are located between the lamps 7 and the reflecting surfaces 6 of the reflectors, to concentrate light on said reflecting surfaces.

Referring to Fig. 7 of the drawings, this form of my invention only differs from that shown by Figs. 1 to 6 inclusive in that two 80 lamps, and two reflectors 10 are provided.

Referring to Fig. 8 of the drawings, this form of my invention only differs from that shown by Figs. 1 to 6 inclusive in that double lines of reflectors and several incandescent lamps are provided.

Referring to Figs. 9, 10 and 11 of the drawings, this form of my invention only differs from that shown by Figs. 1 to 6 inclusive in that a number of circular concave reflectors 90 11 are secured across the opening 12 to the inner face of the wall 2 along the periphery of the opening, in spaced relation to each other, and extend obliquely inwardly and laterally from said walls and each reflector is 95 provided with a surface 13 adapted to reflect light forwardly, downwardly and laterally through said openings. Within the casing, at the side thereof to which the reflecting surfaces 13 of the reflectors 11 face, is provided illuminating means, shown in the 100 drawings as a gas burner 14.

The reflectors and the walls of the casing are made of any suitable material adapted to reflect light, preferably material with a 105 highly polished surface. These reflecting surfaces may be colored as desired which will cause the light reflected to be of a corresponding color and add to the attractiveness of the sign. The spaces between the reflectors allow light to pass outwardly from the casing and while the light is not

so brilliant as the reflected light, from the reflectors, yet it adds to the effectiveness and clearness of the sign.

I do not desire to be understood as limiting myself to the specific details of construction and arrangement as herein described and illustrated, as it is manifest that variations and modifications may be made in the features of construction and arrangement, 5 in the adaptation of the device to various conditions of use, without departing from the spirit and scope of my invention and improvements. I therefore reserve the right to all such variations and modifications as 10 properly fall within the scope of my invention and the terms of the following claims.

I claim:

1. In an illuminated sign, a casing having openings, reflectors located within said 15 casing over said openings and curving from the wall having said openings, obliquely in a lateral and a downward direction and means adapted to project light upon said reflectors which project it outwardly through

said openings in a lateral and a downward direction, substantially as described. 25

2. In an illuminated sign, a casing having openings, triangular reflectors, of the shape of a section of a sphere, secured over said openings and extending obliquely in a lateral direction and means adapted to project light upon said reflectors, substantially as described. 30

3. In an illuminated sign, a casing having openings, concave triangular reflectors secured over said openings and extending obliquely in a lateral direction and means adapted to project light upon said reflectors which project it outwardly through said openings, substantially as described. 35 40

Signed at New York in the county of New York and State of New York this 16th day of March A. D. 1912.

JOHN M. WILLIAMS, JR.
